UNITED STATES PATENT OFFICE.

JAMES K. DIAMOND, OF GRAND RAPIDS, MICHIGAN, ASSIGNOR TO CLIPPER BELT LAGER COMPANY, OF GRAND RAPIDS, MICHIGAN, A CORPORATION OF MICHIGAN.

CARD FOR BELT-HOOKS.

1,198,897.

Specification of Letters Patent. Patented Sept. 19, 1916.

Original application filed December 7, 1914, Serial No. 875,921. Divided and this application filed October 25, 1915. Serial No. 57,819.

To all whom it may concern:

Be it known that I, JAMES K. DIAMOND, a citizen of the United States of America, residing at Grand Rapids, in the county of Kent, and State of Michigan, have invented certain new and useful Improvements in Cards for Belt-Hooks; and I do hereby declare the following to be a full, clear, and exact description of the invention, such as will enable others skilled in the art to which it appertains to make and use the same.

This invention relates to a card construction on which belt fasteners are adapted to be positioned and secured. The method of securing the fasteners to said card and the package produced thereby form the subject matter of a previous application, Serial No. 875,921, filed December 7, 1914, from which application the present one is a division. Previously, belt fasteners have been secured to a card consisting of a base having upwardly bent sections integral therewith, one of said sections being provided with an out-turned portion, the ends of the fasteners being inserted through holes in the upturned sections and the body of the fasteners being received in slots in said outturned portion. It has been customary in attaching belt fasteners to this card to form the card from a flat sheet of material with the base and an upturned section at each side of the base and with an outwardly turned portion integral with one of said upturned sections, the fasteners being attached by machinery and the outturned portion forced against the fasteners and pressed between them, the bodies of the fasteners crushing their way into the outturned portion. In order to successfully accomplish this it has been necessary to especially prepare one edge of the card to give it proper qualities permitting it to be pressed outward between the fasteners and still leave firm sections between the bodies of the fasteners to hold the fasteners separated one from the other. Accordingly a great deal of expense and trouble to thus especially prepare the cards has been necessary but it has heretofore been impossible to eliminate it. It is the object and purpose of the present invention to avoid and do away with this especially prepared edge of the card using in its stead a very simple and economical construction requiring no particular prepa-

ration of the paper or other material but merely a special construction of card which is disclosed in the accompanying drawing, in which:

Figure 1 is a plan view of a card adapted for use to carry the belt fasteners. Fig. 2 is an end elevation showing the formation of the card as it appears with the fasteners attached, the fasteners being shown in dotted outline; and Fig. 3 is a perspective view of the card bent into the shape which it takes when the fasteners 5 are attached but having no fasteners secured thereto.

Like reference characters refer to like parts throughout the several views of the drawing.

The card which is to be used for holding the belt fasteners is formed as a thin flat strip 1 of any suitable material, preferably thin card-board, which is provided with spaced apart rows of circular openings 2 located as shown at a distance from the edges of the strip. The card is further provided closely adjacent one edge with a plurality of elongated openings 3 equal in number to the number of the circular openings 2 at one side of the card. The openings 3 extend inwardly from the edge of the card and at substantially right angles thereto.

When the belt fasteners are attached the card is bent along the dotted lines *a*, *b* and *c*, in this manner forming a base 4 between lines *a* and *b* with upstanding sections 5 and 6 bent inwardly toward each other, there being also provided an outwardly bent portion 7 which is turned from the upper end 90 of section 6. In applying the fasteners to the card, the fasteners being of the formation shown at 9 in dotted outline in Fig. 2, the pointed ends thereof are first inserted through the circular openings 2 and the portion 7 of the card is brought against the inner side of the legs of the fasteners with the openings 3 opposite the respective legs. Part 7 is then bent outward and the legs enter the slots 3, first disrupting the very thin section at 8 which lies between the outer ends of the slots 3 and the edge of the card. It will be evident that this can be accomplished without any disruption or destruction of the intermediate parts of the card between the openings, the bodies of the fasteners being received within each opening 3 while the intermediate portion forms a

tongue to separate and hold the fasteners separated from each other. Furthermore there will be a tendency for the thin part at 8 which has been disrupted on entrance 5 of the fastener into the openings 3 to return to position and insure against any accidental displacement of a fastener.

It will be apparent from this construction that a very simple and economical card 10 is produced for carding belt fasteners and one produced at a much less cost than the one before required where a special preparation of the card at one edge was needed.

I claim:-

15. 1. A card for use in mounting belt fasteners comprised of a strip of flat material having a plurality of parallel elongated openings formed therein closely adjacent one edge of the strip and extending inwardly there- 20 from, said openings lying immediately inside of the said edge with the outer ends thereof closed, the arrangement being such that the material between the outer ends of the openings and the adjacent edge of the 25 card may be easily disrupted, substantially as described.

2. A card for mounting belt fasteners comprised of a strip of flat material having a plurality of substantially circular openings arranged in rows parallel to the edges of 30 the strip and at a distance from each edge thereof, and having a plurality of parallel elongated openings arranged closely adjacent one edge of the strip but lying inside of said edge so that the outer ends of the openings are closed and extending inwardly substantially at right angles to said edge. 35

3. A card for use in mounting belt fasteners comprised of a strip of flat material having a plurality of substantially circular 40 openings arranged in rows parallel to the edges of the strip and at a distance from each edge thereof, and having a plurality of parallel elongated openings arranged closely adjacent one edge of the strip, said openings 45 being equal in number to the circular openings at one side of the strip and lying slightly within the edge of the strip so that both ends of the elongated openings are closed, substantially as described. 50

In testimony whereof I affix my signature.
JAMES K. DIAMOND.
